CONNECTION FOR THE OPERATION OF
HIGH FREQUENCY AMPLIFICATION SYSTEMSWalter Schäffer, Berlin, Germany, assignor to
Radio Corporation of America, New York,
N. Y., a corporation of DelawareApplication November 11, 1926, Serial No. 147,676.
Renewed November 3, 1931. In Germany No-
vember 13, 1925

16 Claims. (Cl. 179—171)

My invention relates to a connection for the operation of high-frequency amplification systems for receiving electric waves, and it is an object of my invention to eliminate the obnoxious 5 tendency of the valve amplifiers to become self-excited.

To this end, I arrange intermediate the anode and the cathode of a valve a series unit comprising a capacity and a self-inductance which unit 10 is tuned to the operating frequency of the system and the voltage induced in this unit will be a maximum when the voltage in the valve may be a minimum. The induced voltage is transmitted to the grid of the following valve 15 through galvanic, capacitative or inductive coupling, and, if desired, may be transformed upward before being thus transmitted.

The undesirable self-induction of the valves is due to a comparatively high voltage between the 20 anode and the cathode of the valve which acts on the grid past the capacity intermediate the anode and the grid so that undesired back-coupling and oscillations are generated.

This may be counteracted by the known neutro- 25 dyne connection by which the back-coupling effect of the voltage between the anode and the cathode of the valve is balanced, but in my invention the voltage is not balanced but eliminated.

In the drawing three diagrams of connections 30 according to my invention are illustrated by way of example.

Fig. 1 is a diagram of a receiver,

Fig. 2 is a similar diagram showing a back-coupling in series with the series unit.

Referring now to Fig. 1, 1 is an antenna, 2 is a tunable grid circuit, 3 is a high-frequency valve amplifier in the grid circuit 2 of which voltage is induced by the antenna 1, 4 is an anode battery, 5 is a radio frequency by-pass condenser 35 connected in parallel to said battery, 6 is an ohmic series resistance past which the battery 4 is connected with the anode circuit 3 at 14. 7 is a rotating plate condenser, 8 is a self-inductance, 9 is a battery supplying the grid voltage for the following valve 3', and 10 is a radio frequency by-pass condenser in parallel to the battery. The parts 7 and 10 constitute the series unit which is connected to the grid circuit of the valve 3' at 11 and 12.

When the valve 3 is excited by the antenna 1 and the tuned grid circuit 2, alternating voltage will form at the ends of the self-inductance 8, since the condenser 10 is without influence in this respect, intermediate the points 11 and 12. 50 The anode current of the valve 3 is direct cur-

rent with superimposed alternating current. The direct current is blocked by the condenser 7 and flows exclusively in the resistance 6 and the battery 4. The alternating current, on the other hand, is branched at 13, and its partial intensities 60 are inversely proportional to the resistances of the branches 6, 4 and 7, 8, with consideration of phase distortion, if any.

When the series unit is tuned to the operating frequency it constitutes a purely ohmic resistance, 65 the total resistance between its ends being a minimum as the apparent impedance is zero. With the series unit tuned, especially if the ohmic series resistance 6 is high in proportion to the ohmic resistance of the series unit, the anode 70 alternating current will flow principally in the unit and under these conditions the alternating voltage at the ends of the coil 8 will be a maximum and equal to $I \omega L$. At the same time, the alternating voltage between the anode and 75 the cathode of the valve 3 is a minimum and is only determined by the value of the ohmic resistance in the series unit.

If the size of the self-inductance 8 were increased and that of the condenser 7 were reduced 80 in order to maintain the tuned condition of the system, the voltage at the ends of the self-inductance 8 would increase unless accidentally the ohmic resistance of the self-inductance 8 had increased with its increase in size. The increase of 85 the voltage may be prevented in practice without difficulty. If the ohmic resistance of the series unit is small enough and consequently the voltage between the cathode and the anode of the valve 3 is small, the tendency of undesired back-coupling and of self-oscillation of the valve 3 is also small with the waves employed.

The connection illustrated permits the transformation of an alternating voltage between the anode and the cathode of a valve by other means 95 than those hitherto employed and the operation will be similar to that of a resonance transformer.

A current self-inductance which might increase the voltage between the anode and the cathode of the valve, is not shown in Fig. 1. If it 100 were provided and the coupling from the self-inductance 8 to the grid of the following valve 3' were suitably modified, for instance inductive, the current self-inductance might be balanced by the condenser 7.

The curve indicating the voltage at the ends of the self-inductance 8 as determined by the adjusting of the condenser 7 is very similar to a resonance curve the width of which is determined by the proportion of the resistance of the 110

series unit to the value of the resistance in the circuit 5, 6.

The voltage at the points 11, 12 is transmitted to the following valve 3' which, as shown, may 5 be a directive valve amplifier. Obviously, another high-frequency valve might be provided in its stead, or a plurality of such valves might be provided, with a directive amplifier or an audion at the end of the line.

10 The operation as described will be performed so long as only voltage, and not power, is transmitted at 11, 12. If power were transmitted, ohmic resistance would be impressed on the series unit at 7, 8, and this would be wrong in principle. But, on the one hand, power can only be transmitted from the anode circuit of a valve if the voltage between the anode and the cathode were greater than corresponds to the ohmic resistance of the series unit at 7, 8 for the power 20 transmitted is invariably equal to the square of the anode current multiplied with the effective resistance transmitted to the anode circuit of the valve, and the anode alternating voltage will obviously increase with this resistance. On the other hand, the connection illustrated prevents the formation of a higher alternating voltage than corresponds to the power transmitted, because stray self-inductance, that is, self-inductance transmitted to the anode circuit, or prevailing capacity, may be balanced by setting the condenser 7.

For receivers, the transmission of effective resistance to the anode circuit, as indicated above, is impossible because the grids of the following 35 amplifier or directing valves which operate the negative range, are excited without power. The cause why the high-frequency valves of the connections as employed hitherto, had a tendency to self-exciting, was the formation of alternating voltage between the anode and the cathode of the valve which was not generated by transmitted effective resistance but was due to prevailing of the capacity or inductance of the anode circuit. This is very probable because the power which 40 45 the grid of a following valve consumes, even if the valve is not in the negative range, is so small in proportion to the power transmitted from the preceding valve that the effective resistance would be only a very small percentage of the ohmic resistance in the anode circuit of the preceding valve. But in fact, as shown, the ohmic resistance is not the cause of too high alternating anode voltage in the preceding tube but the 50 55 prevailing of inductance or capacity in the anode circuit.

With the connection illustrated in Fig. 1 back-coupling may be provided at the first valve as shown in Fig. 2. Referring now to that figure, 14 is a back-coupling coil in series with series 60 unit comprising the self-inductance 8 and the condenser 7. The back-coupling is a definite and purely inductive one because the stray self-induction transmitted to the anode circuit 2 and which might generate an additional inductive 65 voltage, may be balanced by the condenser 7 of the series unit.

The system illustrated in Fig. 2 has the further good feature as compared with the usual systems that the maximum back-coupling voltage exists 70 when the system 14, 7, 8 is tuned as in this case the maximum anode alternating current will occur in the branch 14, 7, 8.

It will be understood that my improved connection is equally applicable to senders and receivers and enables me to build receivers operat-

ing principally at high-frequencies, the high-frequency amplification being practicable to an extent not attained in the existing systems. High-frequency is so desirable for receivers because it intensifies low-frequency interferences which often are troublesome, to a lesser degree than with low-frequency amplification. High-frequency amplification may be extended until it is possible to use telephones the operation of which is based on capacitative action. This eliminates for instance receiver distortions which are brought about by the non-straight-line operation of the usual rectifiers, such as detectors and audions.

It should be noted that in the valves used in connection with my systems the steepness of the characteristic or mutual conductance is important for the degree of amplification. This is in contradistinction to the usual amplifier systems where the degree of amplification with adapted suitable outer resistance is only determined by the inverse or reciprocal amplification factor of the given valve. The feature that in the present case the degree of amplification is a function of the steepness of the characteristic or mutual conductance, is a particular advantage in that it is possible to obtain higher amplifications by increasing the steepness. As in the present instance the alternating voltages between the anodes and the cathodes of the valves are but small it is possible to use valves characterized by a high inverse-amplification factor which may be operated on the other hand at correspondingly low anode voltage.

I claim:

1. A connection for the operation of high frequency amplification systems, comprising, a plurality of valve amplifiers having a path including capacity and self-inductance arranged in series intermediate the anode and cathode of one of said valves, said path including a feed-back coil 110 and being series tuned to the operative frequency 115 of the system, the coil being coupled to the input circuit of the said one valve and a conductive coupling means for transmitting the voltage in a portion of said path to the grid of another valve. 120

2. A connection for the operation of high frequency amplification systems, comprising, a plurality of valve amplifiers having a path including capacity and self-inductance arranged in series intermediate the anode and cathode of one of said valves, said path including a feed-back reactance external of said latter valve and being series 125 tuned to the operative frequency of the system, said reactance being coupled to the input circuit of said one valve means for transmitting the voltage drop in the inductive portion of said path to the grid of another valve. 130

3. A connection for the operation of high frequency amplification systems, comprising, a plurality of valve amplifiers having a path including a variable capacity and a self-inductance arranged in series intermediate the anode and cathode of one of said valves, said path including a feed-back means independent of said latter valve and being series tuned to the operating frequency of the system, said means being coupled to the input circuit of said one valve, and means including a grid biasing source for transmitting the voltage drop in a portion of said path to the grid of another valve. 140

4. A connection for the operation of high frequency amplifier system, comprising, a plurality 145
